Des. 194,637
Patented Feb. 19, 1963

194,637

COOLER FOR BOTTLES AND THE LIKE

Elmer Szantay, 735 S. Karlov Ave., Chicago, Ill.

Filed July 31, 1961, Ser. No. 66,115

Term of patent 14 years

(Cl. D58—26)

Fig. 4.

Fig. 5.

FIG. 1 is a perspective view of a cooler for bottles and the like showing my new design.

FIG. 2 is a side elevational view thereof.

FIG. 3 is an end elevational view thereof.

FIG. 4 is a top plan view thereof.

FIG. 5 is a bottom plan view thereof.

The handle is shown broken away in FIGS. 2, 3 and 4 for convenience of illustration.

I claim:

The ornamental design for a cooler for bottles and the like, substantially as shown and described.
